UNITED STATES PATENT OFFICE.

GEORGE E. KIRK, OF WASHINGTON, DISTRICT OF COLUMBIA.

PADLOCK-COVER.

SPECIFICATION forming part of Letters Patent No. 256,902, dated April 25, 1882.

Application filed September 14, 1881. (No model.)

To all whom it may concern:

Be it known that I, GEORGE E. KIRK, residing at the city of Washington, in the District of Columbia, have invented a Weather-
5 Proof Cover for Padlocks, of which the following is a specification.

My invention is a weather-proof cover for padlocks, or all of that class of locks which implies a staple, with or without a hasp, and
10 embraces the following peculiar features: a cap or open shell hinging to a metal plate so slotted as to fit over a staple, either separately or behind a hasp, or when fastened on its front, all of which are hereinafter more fully de-
15 scribed, and illustrated by the accompanying drawings, forming part of this specification, of which—

Figure 1 represents a front view of the cover, showing its cap closed over the padlock, but with its top broken out to exhibit the slotted plate, with its attachments to the hasp underneath; Fig. 2, a longitudinal cross section of my device; and Fig. 3, a front view of the same, showing the cap raised and the slotted plate placed behind the hasp, which is a horizontal one instead of the perpendicular form shown in Figs. 1 and 2.

In the drawings, A represents the said cap, which consists of a metallic back or top with
20 inclosing sides or flanges and an open bottom, when in the general shape shown here-
with, which shape is made to conform to that of the usual padlock, D.

B represents the said plate, to which the cap

A hinges, and consists generally of a plate of 35 rolled metal, having a suitable slot, c, cut through it to fit over the usual lock-staple E. This slotted plate may be attached, as shown, by any suitable means to the front of the hasp, when a perpendicular one is in use, for the 40 convenience of lifting both hasp and plate together when the padlock is removed, as, should the hasp be lifted with the said plate unattached, the plate would fall away. This last would not happen in the case of a horizon- 45 tal hasp being used, as the plate B could then be put over the staple before the hasp, and would be likely to remain upon the staple after both padlock and hasp had been displaced, and until the padlock could be replaced on the 50 staple, as a keeper of both the padlock and its attendant weather-proof cover.

Of course, when a hasp is not used at all, the slotted plate B can be placed over the staple, and the padlock will, whenever also 55 fastened upon it, always keep the said weather-proof cover in useful position.

Having thus described my invention, I claim as new, and desire to secure by Letters Patent, the following:

A weather-proof padlock-cover consisting of a cap, A, hinging to a plate, B, provided with the staple-slot c, as and for the purposes herein specified.

G. E. KIRK.
